UNITED STATES PATENT OFFICE.

MILO E. RICE, OF KANSAS CITY, MISSOURI.

CORDLESS ANKLE-JOINT.

1,382,855.

Specification of Letters Patent. Patented June 28, 1921.

Application filed April 30, 1920. Serial No. 377,984.

To all whom it may concern:

Be it known that I, MILO E. RICE, a citizen of the United States, and resident of Kansas City, in the county of Jackson and State 5 of Missouri, have invented a certain new and useful Improvement in Cordless Ankle-Joints, of which the following is a complete specification.

The present invention relates to ankle joints of the character used in the construction of artificial limbs, and aims to provide an improved form of connection between the foot and leg portion of artificial legs, one special object of the invention being to provide 15 a practically noiseless joint construction having ample bearing surfaces at the pivotal point of the joint, with suitable provision for preventing any tendency toward relatively lateral shifting movement between 20 the connections.

It is also sought to devise an improved construction in which provision is made for a lubricant chamber within the joint for maintaining a supply of lubricant sufficient 25 for thoroughly oiling the parts.

It is further sought to provide a construction of the character described in which the parts of the joint may be readily and conveniently assembled, or taken apart when 30 necessary, one of the special features of the joint structure being in the use of a pair of co-axial sleeves journaled one inside the other and respectively provided with means for securing the same to the foot and leg portions 35 of the limb.

It is further sought to provide a construction comprising relatively few parts compactly arranged and yet affording all the necessary smoothness and evenness of operation in the movements of the joint, and which will also be comparatively inexpensive to manufacture.

With the foregoing general objects in view, the invention will now be described by reference to the accompanying drawing illustrating one form of embodiment of the improvement, after which the novel features therein will be particularly set forth and claimed.

50 In the drawing:

Figure 1 is a partly sectional elevation illustrating a joint structure embodying the present invention;

Fig. 2 is a transverse section taken on the line indicated by the broken line 2-2 of Fig. 1; and

Fig. 3 is a plan view showing the connecting members of the joint, removed from the limb members.

Referring to the said drawing in detail, 60 this illustrates the improved joint construction in connection with the foot member 6 and the leg member 7 of an artificial leg, the leg member 7 being designed to be mounted in pivotally connected relation to 65 the foot member 6, as illustrated in Fig. 1, with the end of said leg member 7 abutting against a pair of elastic buffer elements 8 and 9 at opposite sides, respectively, of the pivotal connection between said members 6 and 7, that is, to the front and rear, respectively, of said pivotal connection or joint. In the present construction, the joint connecting the said members 6 and 7 comprises a pair of co-axially arranged sleeves 10 and 11, arranged 70 with the sleeve 11 fitting within the sleeve 10, the ends of the latter sleeve extending flush with the side faces of the foot member 6. The sleeve 10 is provided with a bolt element 12, which may be formed integral with said sleeve or be shrunk thereto, the said bolt element being extended centrally through the leg member 7, which is provided with a bore or passage 14 for accommodating the element 12, the latter being 80 formed with a terminal thread for receiving a pair of jam nuts 15 for fixedly securing the bolt element 12 to the member 7, the said nuts 15 being clamped tight against the bottom of a recess 16 within the leg member 7. 90

A similar connection is made between the inner sleeve 11 and the foot member 6 of the limb, this connection taking the form of a bolt element 17 which is formed with a circular head portion 18 having an eye or opening 24 of a diameter corresponding to the diameter of the sleeve 11 and encircling the same, the said head portion 18 being accommodated within a transverse recess 19 formed in the midportion of the exterior 100 sleeve 10, as clearly illustrated in Figs. 2 and 3. The bolt element 17 is secured rigidly to the sleeve 11 by means of a key 20 accommodated within a keyway formed in the exterior of the sleeve 11 and sweat into 105 a recess 22 on the interior of the eye or opening 24 of the head portion of the bolt 17, as illustrated in Figs. 1 and 2. The keyway 21 extends longitudinally from one end of the sleeve 11 and slightly more than half the 110 length of the said sleeve, as shown in Fig. 2. Screw plugs 25 are fitted into the oppo-

site ends of the sleeve 10 into abutment with the opposite ends of the sleeve 11 for the purpose both of retaining said sleeve 11 and of sealing the space within said sleeve, whereby a lubricant chamber for hard oil is provided for maintaining a supply of lubricant which finds its way to those relatively moving parts or surfaces which may require a certain amount of oiling for reducing the friction.

The lower end of the bolt 17 is also provided with a suitable thread for the application of a nut 26, which is countersunk within a recess 27 in the lower or tread face 15 of the foot member 6, whereby the latter is securely connected with the joint structure. The inner or upper face of the nut 27 is suitably cupped out or recessed in order that a minimum amount of stock is required 20 to be cut out of the foot member 6.

It will thus be seen that a neat, and compact joint structure, of comparatively few parts, is provided for forming the pivotal connection between the leg and foot members, and that ample and broad bearing surfaces are provided for the pivot elements, by the provision of the pair of sleeves 10 and 11 arranged co-axially for practically the entire distance across the foot member. 30 The space within the sleeve 11 further enables an adequate supply of lubricant to be maintained for thoroughly oiling the bearing surfaces of the joint. It may also be pointed out that the intermediate portion 35 of the sleeve 10 within which is formed the above described recess 19 is enlarged in size as clearly shown in Figs. 2 and 3 and accommodated within recesses provided for that purpose within both of said members 40 6 and 7, which feature of construction insures effectively against any tendency toward lateral shifting movements of the joint parts relatively to the members 6 and 7. The parts of the pivotal connection are readily 45 assembled, in a convenient manner, the sleeves 10 and 11 being fitted together in the relation shown before one or the other of the members 6 and 7 is attached to its bolt element. This assembly is effected by 50 introducing the head of the bolt 17 within the recess 19 and then inserting the sleeve 11 into the sleeve 10 through the eye of said

head member 18, the keyway 21 of the sleeve 11 affording clearance for the key 20 until the latter becomes seated within the inner 55 end of said keyway 21. After this the plugs 25 are fitted into the opposite ends of the sleeve 10, and the other member 6 or 7 is applied to its bolt and secured thereto. The construction described is simple and efficient, affording all the necessary pivotal movements required of a joint of this character, and allowing an easy and noiseless action, due to the broad bearing surfaces of the pivotal portions of the joint and the 60 65 constant lubrication of said surfaces.

While I have illustrated and described what is now deemed to constitute the preferred form of construction, I desire to reserve the right to make such changes as may 70 fairly fall within the scope of the following claims.

What I claim is:

1. An ankle joint structure for artificial limbs comprising leg and foot members, a 75 sleeve provided with means for fixedly securing the same to one of said members, and a second sleeve journaled within said first sleeve, and a bolt secured to the other of said members and formed with an eye portion 80 encircling said second sleeve, said eye portion of the bolt having an internal key element and said second sleeve being formed with a longitudinal open keyway permitting insertion of said second sleeve within said 85 first sleeve into keyed relation to the eye portion of said bolt.

2. An ankle joint structure for artificial limbs comprising leg and foot members, a sleeve formed with an intermediate transverse recess and provided with means for fixedly securing said sleeve to one of said members, a second sleeve journaled within said first sleeve and provided with a bolt element secured to the other of said members, said bolt having a head portion encircling said second sleeve and keyed thereto within said recess, and plugs secured in the ends of the first-named sleeve and forming closures for said second sleeve. 90 95 100

In witness whereof I hereto affix my signature.

MILO E. RICE.
